UNITED STATES PATENT OFFICE

119,175

DESIGN FOR A COMBINED AIR VOLUME CONTROL AND PRESSURE GAUGE

Burton E. Shaw, Bristol, Ind., assignor to Penn
Electric Switch Co., Goshen, Ind., a corporation
of Iowa

Application October 23, 1939, Serial No. 87,830

Term of patent 7 years

To all whom it may concern:

Be it known that I, Burton E. Shaw, a citizen
of the United States and a resident of Bristol,
in the county of Elkhart and State of Indiana,
have invented a new, original, and ornamental
Design for a Combined Air Volume Control and
Pressure Gauge, of which the following is a spec-
ification, reference being had to the accompan-
ying drawing, forming part thereof.

Figure 1 is a perspective view of a combined air

volume control and pressure gauge showing my
new design; and

Figure 2 is a side elevational view thereof.

The dominant features of my design reside in
the parts shown by solid lines on the drawing.

I claim:

The ornamental design for a combined air
volume control and pressure gauge, substantially
as shown and described.

BURTON E. SHAW.
